UNITED STATES PATENT OFFICE.

WILLIAM J. CARTWRIGHT, OF NEW YORK, N. Y., ASSIGNOR OF ONE-HALF TO FRANK L. WING,
OF NEW YORK, N. Y.

TURBINE.

No. 891,812.

Specification of Letters Patent.

Patented June 30, 1908.

Application filed March 27, 1907. Serial No. 364,942.

To all whom it may concern:

Be it known that I, WILLIAM J. CARTWRIGHT, a citizen of the United States, residing in the borough of Manhattan, of the city of New York, in the State of New York, have invented certain new and useful Improvements in Elastic-Fluid Turbines, of which the following is a specification, reference being had to the accompanying drawings, forming a part hereof.

The object of this invention is to improve the means for controlling and regulating the speed of elastic fluid turbines.

The invention is concerned with the means for controlling the admission of motive fluid through the speed of the turbine and with the means for determining the admission of the motive fluid to condensing or non-condensing nozzles according to the pressure conditions within the turbine.

The invention will be more fully described hereinafter with reference to the accompanying drawings in which, for purposes of explanation and illustration of the nature of the invention, there is shown a practical embodiment thereof together with modified forms of certain parts.

In the drawings—Figure 1 is a view in vertical central section of a steam turbine which embodies the invention. Fig. 2 is a view in end elevation of the turbine shown in Fig. 1. Fig. 3 is a transverse section on the plane indicated by the line 3—3 of Fig. 1.

In the embodiment of the invention illustrated in Figs. 1—3 of the drawings the shaft *a* of the turbine is mounted to rotate in suitable bearings supported by the body *b* and head *b'* of a generally circular casing which is shown as mounted upon a suitable base *b''*. The body *b* is preferably stepped or successively reduced in diameter from the annular inlet or feed chamber *b'* which is secured to and forms a part of the head *b'*, to the annular exhaust chamber *b''*. To the inside of the casing body *b* are secured the rings *c* which support the stationary vanes *c'* and *c''*, which form the stationary buckets or vane spaces, to be more particularly described hereinafter. To the shaft *a* are secured rotating turbine

wheels *d*, *d*. Through the head *b'* are formed the nozzles through which the steam or other elastic fluid is admitted to the buckets of the first wheel *d*. These nozzles are condensing nozzles, as indicated at *b'* in Fig. 1, and non-

condensing nozzles, as indicated at *b''* in Fig. 1, preferably arranged in alternation, so that through the movement of the ring *e*, provided with ports *e'*, which overlies the inlets of the nozzles *b'* and *b''*, the steam can be admitted either to the condensing nozzles or to the non-condensing nozzles as the conditions of operation require. Preferably the nozzle charger is made automatic in its operation, being governed by the vacuum in the exhaust. As shown in Fig. 3 the ring *e* is connected by a rod *e'* to a lever *e''* which in turn is connected by a link *e'''* to a piston *f* of a cylinder *f'*. Connection is established to the cylinder *f'* from the annular steam chamber *b'* or some other part of the steam connection, and from the exhaust chamber *b''* or some other part of the connection wherein a vacuum pressure is created, the connection to steam pressure or vacuum pressure being governed by a valve the movement of which is controlled by the degree of vacuum pressure.

As shown in Fig. 3, the cylinder *f'* is connected by a pipe *f''* with a valve chamber *g* to which a steam pipe *g'* and a vacuum pipe *g''* are connected. The sliding valve plug *g'''* in the valve box *g* is connected to a diaphragm *h* which is subject on one side to atmospheric pressure and on the other side, through a vacuum pipe *h'*, to the vacuum which exists in the exhaust passages of the turbine. So long as the vacuum is above the predetermined degree the diaphragm is moved by the atmospheric pressure to hold the valve plug *g'''* in such position that connection is established between the cylinder *f'* and the exhaust passage in which the vacuum exists, so that the piston *f* is drawn to and held in such a position that the ports *e'* of the ring *e* register with the condensing nozzles *b'*. Should the vacuum be less than the predetermined degree, however, the valve *g'''* will be moved by the diaphragm in a direction to establish communication between the cylinder *f'* and the source of steam pressure through the pipe *g'*, so that the ring *e* will be shifted to close the condensing nozzles *b'* and to cause the ports *e'* to register with the non-condensing nozzles *b''*. By this means a shifting of the steam connections from condensing or non-condensing nozzles, or vice versa, is effected automatically and instantly as soon as the conditions require the change.

Not only is the admission of steam from the annular steam chamber b^3 to the condensing or non-condensing nozzles controlled automatically, but the admission of steam 5 from its source of supply to the steam chamber b^3 is also controlled automatically. Steam is admitted from the source of supply, through a connection indicated at i , to a valve chamber i' in which is a valve k 10 which controls the admission of steam to the valve chamber. The stem k' of the valve, in the construction shown in Fig. 1 of the drawings, is connected to one arm of a lever k^2 , the other arm of which is connected to the head k^3 of the rod of a piston l which is preferably weighted, as indicated at l' , so that it shall tend to open the valve k . The piston l fits loosely in the cylinder m which is connected, below the piston, by a pipe m' , with 20 the discharge n' of a rotary pump n which is driven by the shaft a , being directly connected therewith in the construction shown. The inlet n^2 of the pump is connected to a tank o which is adapted to receive a suitable 25 liquid, such as oil. The tank o is connected by a pipe o' with the cylinder m at a point above the piston l and is also connected to the discharge pipe m' through a by-pass connection o^2 fitted with a regulating valve o^3 . 30 Whenever the turbine exceeds a predetermined speed, which is regulated by the weight l' , the liquid is forced into the cylinder m faster than it can escape past the piston and through the pipe o' into the tank o , 35 thus forcing the piston up and closing, more or less, the valve k , while if the speed of the turbine falls below the predetermined degree the pressure below the piston is reduced and the weight lowers the piston and opens the 40 valve k . The by-pass o^2 is preferably kept slightly open at all times in order that the liquid may be kept in circulation continuously and so that the pump shall not become air bound.

45 I claim as my invention:

1. In an elastic fluid turbine, the combination of a turbine wheel, condensing and non-condensing nozzles, a pressure chamber, shiftable devices to establish communication 50 between the pressure chamber and the condensing or the non-condensing nozzles, and means controlled by the vacuum pressure of the turbine exhaust to shift said devices.

2. In an elastic fluid turbine, the combination of a turbine wheel, condensing and non-condensing nozzles, a pressure chamber, shiftable devices to establish communication between the pressure chamber and the condensing or the noncondensing nozzles, a cylinder and piston operatively connected to 55 said devices, and means controlled by the vacuum pressure of the turbine exhaust to

control the admission of operating fluid to said cylinder.

3. In an elastic fluid turbine, the combination of a turbine wheel, condensing and non-condensing nozzles, a pressure chamber, shiftable devices to establish communication between the pressure chamber and the condensing or the noncondensing nozzles, a cylinder and piston operatively connected to 65 said devices, separate connections between said cylinder and the motive fluid connections and the exhaust connections of the turbine, a valve to control said connections and means actuated by the vacuum pressure of the turbine exhaust to control said valve. 70

4. In an elastic fluid turbine, the combination of a turbine wheel, condensing and non-condensing nozzles, a pressure chamber, shiftable devices to establish communication between the pressure chamber and the condensing or the noncondensing nozzles, a piston and cylinder operatively connected with 80 said devices, separate connections from said cylinder to the pressure chamber and the exhaust connections of the turbine, a valve to control said connections and a diaphragm operatively connected with said valve and subject to the vacuum pressure of the turbine 85 exhaust. 90

5. In an elastic fluid turbine, the combination of a turbine wheel, an annular pressure chamber, condensing and noncondensing nozzles between the pressure chamber and the turbine wheel, a valve ring mounted in the pressure chamber and having ports to establish communication between the pressure chamber and the condensing and noncondensing nozzles, and means controlled by the 95 vacuum pressure of the turbine exhaust to shift said valve ring. 100

6. In an elastic fluid turbine, the combination of a turbine wheel, an annular pressure chamber, condensing, and noncondensing, 105 nozzles between the pressure chamber and the turbine wheel, a valve ring mounted in the pressure chamber and having ports to establish communication between the pressure chamber and the condensing and noncondensing nozzles, and a cylinder and piston, 110 operatively connected to said valve ring, a valve to control the admission of operating pressure to said cylinder and a diaphragm subject to the vacuum pressure of the turbine 115 exhaust and operatively connected with said valve.

This specification signed and witnessed this 19th day of March, A. D. 1907.

W. J. CARTWRIGHT
